UNITED STATES PATENT OFFICE.

CHARLES C. HOWARD, OF LOUISVILLE, KENTUCKY.

CHECK BOOK AND METHOD OF FORMING THE SAME.

Application filed April 20, 1928. Serial No. 271,535.

This invention relates to book bindings and more particularly to a check book or the like consisting of a number of sheets or leaves bound in book formation.

One object of the invention is to provide a check book or the like having its leaves so bound that the book may be opened at any place desired or the leaves successively turned and always remain open in a flat condition so that they may be easily written upon with pen and ink or by means of a typewriter and not be liable to move to a closed position and cause wet ink upon a leaf of the book to be smeared.

Another object of the invention is to firmly interlock the leaves of the book so that they will be retained in book formation, but at the same time leave each leaf entirely free from the leaves immediately adjacent thereto, and thereby allow the book to be fully opened at any point desired.

Another object of the invention is to connect alternate leaves of the book by connecting tongues which extend between connected tongues of the remaining leaves so that the connecting tongues of each series of leaves will be interlocked with the connecting tongues of the second series of leaves and all of the leaves, thereby retained in proper stacked formation.

Another object of the invention is to permit a large number of sheets of paper from which check books are to be formed to be assembled in stacked formation with the sheets or leaves joined and the stack of joined sheets then easily separated into sections each composed of an appropriate number of sheets to form a check book.

Another object of the invention is to provide an improved method by means of which sheets formed with tongues may be very easily assembled in a stack and have their tongues joined to connect alternate sheets during formation of the stack.

The invention is illustrated in the accompanying drawing, in which,—

Figure 1 is a view showing a check book of the improved construction opened.

Figure 2 is an enlarged fragmentary sectional view taken on the line 2—2 of Figure 1.

Figure 3 is a fragmentary sectional view taken through the connecting tongues of a stack of leaves at right angles to the view shown in Figure 2.

Figure 4 is a perspective view illustrat-

ing the manner of assembling the sheets of the book in stacked formation.

The sheets of paper 10 from which the check book is formed are of an appropriate size and are to be bound between backs 11 joined by a flexible binding 12 so that the book may be opened between selected leaves, as shown in Figure 2, or the leaves of the check book successively turned, as the blank checks printed thereon are filled in and torn from their stubs. For convenience certain of the leaves have been designated by the numbers 1, 2, 3, 4, 5, and 6, and the fly leaves are indicated by the numerals 13, and 14.

The sheets of paper having blank checks and stubs printed thereon are delivered from the printing press in a stack and they preferably have numbers applied to them during the printing, although the numbers may be omitted if so desired. The printed sheets are then fed through a cutting machine which removes portions from each sheet at one side thereof to provide tongues spaced from each other, and for convenience, the tongues of the sheets 1, 3 and 5 have been designated 15 and the corresponding tongues of the sheets 2, 4 and 6, designated at 16. From an inspection of Figure 4, it will be seen that the tongues 15 and 16 are disposed in staggered relation to each other and the tongues of each sheet are of such width that they may be snugly received between the tongues of adjoining sheets.

Therefore, the tongues may have interlocked relation to each other and prevent the sheets from slipping out of their proper positions. The cut sheets are then disposed one upon another in groups of two and the free end portions of the tongues which are of an even length are folded under to provide folded end portions or tabs 17 and the groups of sheets fed through a pasting machine. As the groups of pairs of sheets are fed through the pasting machine paste is applied to the tongues 15 and 16 of one pair of sheets which may be the sheets 1 and 2, as shown in Figure 4. The second pair of sheets 3 and 4 is then slid into place and the tabs of the tongues 16 of the sheet 4 will rest upon the tongues 16 of the sheet 2 and the tongues 15 of the sheet 3 will pass between the tongues 16 of the sheet 2 so that their tabs will rest upon the tongues 15 of the sheet 1. The adhesive is now applied to the upper surfaces of the tongues of the sheets 3 and 4, and while doing so pressure will be applied which causes the tongues of

the sheets 3 and 4 to adhere to the tongues of 1 and 2, respectively. The sheets 5 and 6 are then moved into place in a like manner and their tongues will adhere respectively to the 5 tongues of the sheets 3 and 4. This is repeated until the entire stock of sheets has been assembled and the alternating sheets will have their tongues adhering to each other.

In other words the sheets having even numbers will have their tongues connected and be 10 free from the sheets having odd numbers, and by an inspection of Figure 2, it will be seen that the sheet 3 has its tongues adhering to the sheet 1 and is engaged by the tongues of 15 the sheet 5, whereas the sheet 4 has its tongues adhering to the sheet 2 and is engaged by the tongues of the sheet 6. Therefore, each individual sheet will be unsecured to the sheet immediately adjoining it, but it should be noted 20 that since each sheet has its tongues extending through the spaces between the tongues of an adjoining sheet the tongues will have interdigitating relation to each other to retain the sheets in proper book formation.

25 After all of the sheets have been assembled with the tongues adhering to alternating sheets the stack of connected sheets may be divided according to the number of sheets desired to have in a check book and bound in 30 the covers in book formation with the fly leaves 14 adhering to the backs 11 and the flexible portion 12 of the cover disposed against the interconnected tongues. A fabric binding strip 17 will be applied before the 35 stack of sheets from which a check book is formed is mounted in its cover.

A check book formed as illustrated in the accompanying drawing and described above will have its leaves securely held in book formation, but since the leaves are not joined to 40 leaves immediately adjoining them the book of blank checks may be opened at any point desired or the leaves successively turned and the leaves will always lie flat, as shown in Figure 2, and they will have no tendency to return to a closed position. Therefore, a sheet of blank checks may be very easily written upon with pen and ink or by means of a typewriter, and there will be no danger of the ink 45 being smeared. While it is stated that the invention refers to a check book, it will be obvious that it could consist of any blank forms desired which are to be filled in or a note book or ledger, and it will also be obvious that record sheets and maps or the like which it is desired to preserve could be bound as set forth 50 above.

Having thus described the invention, I claim:

60 1. A book comprising leaves stacked and each leaf having spaced tongues at a side thereof, each leaf having its tongues passed between tongues of an adjoining leaf and adhering to a sheet preceding the same.

65 2. A book comprising leaves stacked and

each leaf having spaced tongues at a side thereof, the tongues of alternate leaves being disposed in face to face engagement with each other with their contacting faces adhering to each other.

70

3. A book comprising leaves stacked and each leaf having spaced tongues at a side thereof, alternate leaves being joined by having their tongues attached in face to face engagement with each other.

75

4. A book comprising leaves assembled in a stack, alternate leaves having their inner ends overlapped and joined in face to face engagement with each other and each leaf being unsecured to adjoining leaves of the 80 stack.

85

5. A book comprising leaves assembled in a stack and provided with tongues joining alternate leaves of the stack, the tongues of one series of joined leaves being disposed in staggered relation to the tongues of the other series of joined leaves and extending between the same and having their end portions folded transversely to provide tabs, the tabs being disposed in face to face engagement with the tongues of the leaves to which they are joined and secured thereto.

90

6. A book comprising leaves assembled in a stack and interdigitating members retaining the leaves in stacked formation with the 95 members of alternate leaves adhering to each other.

95

7. A method of forming a book consisting of cutting sheets to provide each with tongues at one side, arranging the sheets in a stack with the tongues of adjoining sheets disposed in staggered and interfitting relation to each other, and securing the tongues of alternating sheets in adhering relation to each other to connect the said alternating 100 sheets.

100

8. A method of forming a book consisting of cutting sheets to provide each with tongues at one side, arranging the sheets in a stack with the tongues of adjoining sheets disposed in staggered and interfitting relation to each other, and securing the tongues of alternating sheets in face to face engagement with each other with each sheet free from adjoining sheets and having its tongues extending between the tongues of one of the said adjoining sheets and adhering to the tongues of the sheets to which it is secured.

110

9. A method of forming a book consisting of assembling a number of sheets, providing each sheet with tongues extending from one side in spaced relation to each other, placing one sheet upon another with the tongues of one sheet fitting between the tongues of the other sheet, bending the tongues of each pair of sheets to form tabs at the ends of the tongues, and stacking the pairs of sheets with the tabs adhering to the tongues upon which they rest and connecting alternating sheets of the stack.

120

125

130

10. A method of forming a book consisting of assembling a number of sheets, providing each sheet with tongues extending from one side in spaced relation to each other, bending the free end portions of the tongues to form tabs, and stacking the sheets with the tongues of alternating sheets extending between the tongues of the remaining sheets and having their tabs secured in 10 face to face engagement with the tongues of their companion sheets.

11. A method of forming a book consisting of assembling a number of sheets, providing each sheet with tongues extending 15 from one side in spaced relation to each other, placing the sheets one upon another with the tongues of one sheet fitting between the tongues of the other sheet, folding the free end portions of the tongues of a pair of sheets 20 to provide attaching tabs, and setting another

pair of sheets in place upon the first pair with the tabs of their tongues secured to corresponding tongues of the first pair of sheets.

12. A method of forming a book consisting of assembling a number of sheets, providing each sheet with tongues extending from one side in spaced relation to each other, placing one sheet upon another with the tongues of one sheet fitting between the tongues of the other sheet, simultaneously 25 folding the free end portions of the tongues of a pair of sheets to provide attaching tabs, applying adhesive to the inner end portions of the tongues, and setting another pair of sheets in place upon the first pair of sheets 30 with the tabs of their tongues adhering to the corresponding tongues of the first pair of sheets. 35

In testimony whereof I affix my signature.
CHARLES C. HOWARD.
